EDGE TOOL DEVICE

Filed Dec. 27, 1941

UNITED STATES PATENT OFFICE

2,342,197

EDGE TOOL DEVICE

Earl Edward Hindman, Washington, D. C.

Application December 27, 1941, Serial No. 424,657

7 Claims. (Cl. 30—41)

The invention relates to cutlery devices, and particularly to means adapted to be embodied in safety razors, scrapers, and other tools, incorporating means in the tool to function as a receptacle or receiver for lather and shaved hairs or other detritus, so that dropping of lather upon the person of the user or upon other objects and surfaces is minimized.

A further important aim is to so construct a lather receptacle and tool mount that the article may be readily cleaned and cleared of all accumulations. Another important aim of the invention is to provide a mount adapted to use with a well known construction of safety razor guard or comb portion, so as to cooperate therewith to receive and hold lather passing over the edge of the blade during shaving operations.

Additional objects, advantages and features of invention reside in the construction, arrangement and combination of parts involved in the embodiment of the invention, as will be more readily understood from the following description and accompanying drawing, wherein

Figure 1 is a view partly in cross section of a razor head embodying my invention, in closed position, the blade being omitted, and the lower part of the handle being broken away, doubled in size.

Figure 2 is a similar view with the parts in open position.

Figure 3 is an elevation of the article as viewed from the right hand side of Figure 1, approximately actual size of the article as used.

Figure 4 is a horizontal section on the line 15—15 of Figure 2, actual size.

There is illustrated a development of the invention applied to a well known commercial type of razor, so constructed that a blade may be clamped therein without detachment of any of the parts of head or clamping elements.

This well known razor, now largely sold upon the market, includes a guard and blade support member 50, of rigid construction, and fixed upon a support body 51, which, in the present instance, is extended as a handle 15. Through this support 51 a plunger 52 is longitudinally reciprocable, carrying a frame work 53 which includes a central bar, fixed at right angles across the outer end of the plunger 52, the frame including also lateral arms 54 at each side upon the in-turned reduced ear portions 55 of which clamping yokes 56 are pivoted. Each yoke 56 includes a top clamping plate 57 adapted in one position of the device to lie closely over the guard 50 so as to press a razor blade of the Gillette type

downwardly upon the guard and flex the blade to the familiar form which the guard causes it to assume, the clamp plates being curved and adapted to press the outer longitudinal edge portions of the blade downwardly around a corresponding curved part of the guard, so that the blade edges are exposed properly for shaving operation upon the face of the user, as is generally well understood in the art. The yokes 56 include arms 58 at each end lying outwardly of the ends of the guard 50, and the guard at each end is provided with longitudinal outwardly projected lugs 59, beside which the arms 58 may reciprocate in the movement of the frame with the plunger 52. The arms 58 are provided with heel portions 60, projected laterally of the razor head beneath the lugs 59, so that as the frame is moved outwardly with the plunger 52, the heel portions will strike the lugs 59 and cause the clamp plates 56 to swing outwardly to the position shown in Fig. 13. The moving frame 53 on the plunger 52 is the means for drawing the clamping plates into snug engagement with the razor blade laid over the guard 50, and the frame is in its lowermost position when so engaged with the razor, as shown in Figure 1, or nearly so, depending upon the thickness of the razor blade. In its elevated position, the frame is raised so that the clamp devices 56 are elevated above the guard, and in movement to this position, after the heel portions 60 have engaged the lugs 59 and moved the clamp devices outwardly a distance, the article being held with the plunger 52 on a vertical axis, gravity will draw the clamp devices 56 further outwardly, until they fall to full open position, with the arms 58 of the clamp devices resting upon the upper side of the lugs 59, as shown in Figure 2. The moving frame 53 on the plunger includes parts slidable through the guard 50 so as to hold the frame and plunger against rotation relatively to the guard on the axis of the support 51 and guard. In this type of razor as heretofore produced a rotating knob on the end of the conventional handle is so engaged with the reciprocating element corresponding to the plunger 52 here shown that the reciprocating element is moved longitudinally outward upon rotation of the knob in one direction, and is retracted upon rotation of the knob reversely. In my invention the support 51 instead of being formed like a handle in itself, is formed with a short externally threaded tenon 61, and the plunger 52 extended downwardly a distance beyond this tenon, the outer end portion of the plunger having screw threads formed thereon,

Otherwise, the parts of the prior commercial article mentioned are retained in substantially identical construction as heretofore produced and well known.

In the present instance, I have a ferrule 62 of cylindrical form screwed upon the tenon 61, and having a reduced bore 63 therethrough, forming a shoulder 64 adjacent the end of the tenon, but spaced from the tenon when the ferrule is screwed snugly against the under side of an enlargement 65 formed on the support 51. Held revolubly in the ferrule, there is an operating sleeve 66 having a flange 67 at its upper end by which it is held against longitudinal movement in the ferrule, this flange being fitted revolubly between the shoulder 64 and the adjacent end of the tenon 61. The sleeve is interiorly threaded and engaged upon the threaded extremity of the plungers 52, so that rotation of the sleeve 66 will cause longitudinal movement of the plungers 52. To accommodate the threaded portion of the plunger, the sleeve is formed of a piece bored and tapped, the bore being of a sufficient depth to leave a clearance between its inner end and the extremity of the plunger 52 when the latter is in its lowered position, as may be clearly seen in Figure 1. The sleeve 66 is provided with a longitudinally extended portion of reduced diameter, formed with anchor flukes or lugs 69 projected laterally therefrom, and this extension 68 is embedded in the molded plastic material of the handle 15, which may be transparent, translucent, or otherwise.

From the last given description, it will be apparent that by grasping the ferrule 62 between the thumb and forefinger of one hand, while the transparent cover 15 of my illuminating device is rotated, the plunger 52 will be caused to move outwardly from the position of Figure 1, or inwardly from the position of Figure 2, to enable use of the razor head in the way familiar in the use of the aforementioned well known commercial razor device.

In accordance with my invention, the enlargement 65 is principally in the form of wing-like cam flanges, the lower sides of which may be of any convenient or symmetrical shape, while the upper sides are concavely curved, as shown in Figures 1 and 2. Respective cup devices 70 of elongated form are arranged under respective sides of the guard and pallet member. The latter, as customary, is formed with a rectilinear lower edge 71, on the guard portion proper, the adjacent edge portion being extended downwardly near, if not quite, parallel to the axis of the mounting, the mounting in the present instance comprising the support 31, the ferrule 62 and any additional parts incorporated thereon. Each cup is provided with a corresponding rectilinear upper edge portion 72, adapted to lie in snug fitting abutting engagement with the edge 71 of the guard, respectively, and a front wall portion of the cup 73 is extended downwardly therefrom as viewed in Figure 1, being inclined inwardly toward the axis of the mounting with a gradual curve for a short distance. Each cup is provided with inner wall portions 74, forming the inner side of the cup, and, formed integrally with the two walls, there is an end wall 75 at each end, the two walls 75 being parallel to each other, and having portions extended obliquely above a line from the edge 72 to the top of the wall 74, and also extended in the general upward direction of the wall 74 for a distance, to form pivot ears 76, which are continuations of the walls 75. The cups are made of a length somewhat greater than that

of the guard 50, and may be also made of a length equal to the distance between the outer faces of the arms 54 at one end and corresponding faces of the arms at the opposite end of the head of the razor. This permits the ears 76 to be pivoted on the outer sides of the arms 54, by means of fixed pintles or rivets 77, shown in Figures 1 and 2.

The walls 74 are flat for the major portion of their length, and so spaced from the lip 72 of the cup and so arranged in angular relation thereto that these walls 74 may lie in close parallel relation when the cups are in lowered or open position, as shown in Figures 2 and 4. In order to accommodate the support 51 between the cups when so opened, the walls 74 are provided with a recessed or inwardly bowed portion 78 in each, and having an inner bight part 80 receiving the upper reduced portion of the support 51 when the latter is lowered. The cam edge 79 of the flange elements 65 is so shaped and positioned that when the plunger 52 is at its lowermost position and the cups 70 are engaged against the guard, as shown substantially in Figure 1, the lower part of the cup in the bight 80 of each cup will rest upon the outer, nearly or quite horizontal portion of the cam surface 79, and the cam surface is so shaped that as the plunger 52 is extended, moving with it the same work and pivot 77, the bight portion 80 will slide inwardly upon the cam, permitting the cups to move downwardly and inwardly by gravity, to the position shown in Figure 2. Upon downward movement of the frame and pivot again, the pressure of the bight portion 80 against the cam surface 79 will cause the cups to swing outwardly, the bight portion 80 riding upon the surface 79 until the cups are raised again to full closed position as shown in Figure 1, when the plunger reaches a lower position, as indicated in the same view.

The guard 70 being formed with longitudinal slots 81 throughout the curved extreme edge portion of the guard, when the device is in use, lather and shaved whiskers passing between the blade edge and guard will enter the slots and accumulate in the cups 70. When the razor parts are moved to open position as shown in Figure 2, the cup is lowered from the guard, so that it is made possible to readily wash out the accumulated lather. In this way, the spilling of lather upon the person of the user of the razor is guarded against, as well as the soiling of floors, rugs and other objects avoided.

It will be understood that the disclosure of the invention herein made is purely exemplary, and that various modifications in the construction, arrangement and combination of parts as well as substitutions of materials, and mechanical equivalents may be made without departing from the spirit of the invention, as more particularly set forth in the claims, but, having now disclosed with great particularity the embodiment of my invention in its best form as thus far developed, what I claim as new and novel is:

- 65 1. In a hand tool mounting including an edge tool support and clamping device movably engaged therewith, for clamping and release of such tool, a pivoted cup device constructed to move into detritus receiving relation to the edge tool engaged in the device at one position, and to move to a retracted open position in relation to the tool, and cup operating means connected between the movable clamping device and the cup.
- 70 2. An edge tool mounting and detritus gath-

ering means comprising a body having a tool support element adapted to receive an edged tool thereupon and constituting one member of a clamp, and a relatively movable clamping member constructed to engage the tool opposite the pallet for clamping of the tool in one position, and to move a distance outwardly from the tool for release of the latter at another position, a cup device having an edge portion adapted to align substantially with that of an engaged tool and pivoted upon one of said clamping members, and connections between the cup and the other of said clamping members operative to move the cup into open and inoperative position when said clamping member is at the outer limit of its movement.

3. In a razor of the character described, a guard and support constituting one element, and a relatively movable element movable longitudinally on the support from one position relative to the guard to a position substantially distant, clamping members mounted upon one of said first named two elements for clamping a tool laid upon the guard at one relative position of the said two elements, and movable to release the tool at another position, and clamp operating means connected between the other of said first named two elements and said clamping members, a cup device pivoted on one of said first named two elements positioned to lie beneath a blade mounted in the device, and movable to swing downwardly to a discharge position beneath said blade, and a cam device on the other of the first named two elements arranged to engage a lower part of the cup for support of the latter in operative position at clamping position of the parts, and to clear the cup for movement of the latter to open position at released position of the parts.

4. In a razor mounting wherein there is provided a guard and pallet member, a fixed support therefor, a slidable frame thereon having clamping members operative over the pallet and operatively connected between the pallet and frame to clamp an interposed blade at one position of the frame and to move the clamping members to released position at another position of the frame; a detritus receiver consisting of an

elongated cup positioned at the side of the mounting below the guard and pivotally connected at its inner part to an inner part of said frame and being free to move relatively to said frame to and from operative position, and a cam device on the support engaged with a lower part of the cup adapted to support the cup in operative position and shaped to recede from the engaged part of the cup under relative downward movement of the cam with respect to the frame.

5. In a razor mounting consisting of a perforated guard member, a support therefor, a clamp operating frame movable relatively to the mean plane of the guard and having clamping means operatively connected with the guard and said frame; the inclusion of a detritus receiver thereon consisting of an elongated cup arranged under the guard aligned with one guard edge thereof and shaped and adapted to lie in one position in close relation to the guard and in detritus-receiving relation to the openings through the guard, and to move to a distant position spaced from the guard, said cup having a part extended toward and pivotally connected to said frame, and means operative between the cup and support to move the cup to and from operative position under relative movement of the guard and said frame.

30 6. The structure of claim 5 in which the last named means consists of a cam on the support having wiping engagement with the cup constructed with a part positioned to support the latter in closed position when the said frame is in lowered position, and inclined inwardly and upwardly from the said part.

7. In a razor, a blade carrier member including means to clamp a blade on the carrier member, an elongated cup arranged to lie under and parallel to the edge of an engaged blade, an operating member for the clamping means movable on said carrier, said cup being pivoted on one of the two said members, so named, and operative connections between the cup and the other of said members to move the cup from receiving relation to the blade to discharge position.

EARL EDWARD HINDMAN.
